UNITED STATES PATENT OFFICE.

HERBERT G. BEYER, OF BALTIMORE, MARYLAND, ASSIGNOR TO RAE-LITE MANUFACTURING CO., OF BALTIMORE, MARYLAND, A CORPORATION OF MARYLAND.

DESIGN FOR A PARKING LIGHT.

Application filed May 18, 1925. Serial No. 13,482. Term of patent $3\frac{1}{2}$ years.

To all whom it may concern:

Be it known that I, HERBERT G. BEYER, a citizen of the United States, and resident of Baltimore, in the city of Baltimore and State of Maryland, have invented a new, original, and ornamental Design for Parking Lights, of which the following is a specification, reference being had to the accompanying drawing, forming part thereof.

In this drawing—

Figure 1 is a front view.
Fig. 2 is a side elevation.
Fig. 3 is a plan view, and
Fig. 4 is an elevation of the rear of the light.

I claim:
The ornamental design for a parking light, as shown.

HERBERT G. BEYER.
